RAILWAY TRACK LUBRICATING DEVICE

William F. Huck, Richmond Hill, N. Y.

Application February 2, 1937, Serial No. 123,567

5 Claims. (Cl. 184—3)

This invention relates to railway track lubrication, having for its principal object the provision of a device of the kind indicated, particularly designed and adapted to minimize the pounding 5 action of swiftly moving railway vehicle wheels operatively engaging the mechanism, thereby insuring a uniform dependable action of the parts subjected to the thrusts of the successive car wheels, an economical yet positive disposition of lubricant to the desired portions of the rail head, and a long life to the operating parts of the 10 device.

Another object is to provide a device for lubricating the inner side of the rail head at or in 15 the vicinity of a curve, with novel, shock absorbing means to insure the ejection of a predetermined amount of lubricant against the rail head while safeguarding the device against undue wear and breakage during the operating periods.

A further object is to provide in a device of the 20 character indicated, a lubricant reservoir so constructed and arranged that superfluous lubricant will run down along the rail head and drain back into the reservoir with a view to economizing the 25 lubricant supply.

An additional object of the invention is to provide a device of the kind indicated, characterized by a plurality of units acting independently of each other and normally adapted to be operated 30 in sequence; all of the said units being housed within a protecting casing which latter also serves as an oil reservoir.

It is also an object of the invention to provide 35 a railway track lubricator of generally improved construction, whereby the device will be simple, durable and inexpensive in construction, as well as convenient, practical, serviceable and efficient in its use.

With the foregoing and other objects in view, 40 which will appear as the description proceeds, the invention resides in the combination and arrangement of parts, and in the details of construction hereinafter described and claimed, it being understood that various changes in the 45 precise embodiment of the invention herein disclosed may be made within the scope of what is claimed without departing from the spirit of the invention.

Heretofore, devices designed for the automatic 50 lubrication of railway tracks and for the flanges of vehicle wheels passing over same, required frequent repair and replacement, due to excessive wear and actual breakage as a consequence of the severe battering to which they were 55 subjected by the impact of the wheel flanges of

the railway cars moving at high speed. As a consequence, such devices often failed to provide lubrication over comparatively long periods of time during which they were supposed to be functioning.

In accordance with the present invention, lubricant is applied only to the inner side of the rail head and not directly to the wheel flanges where it would be flung off by centrifugal action. Furthermore, as will appear hereinafter, while 10 the mechanism is particularly designed to function efficiently under the impact of rapidly moving railway vehicle wheels, novel shock-absorbing means in the form of preloaded, double-acting self-dampening springs are provided, permitting 15 the lubricant-dispensing parts to yield as a unit, should, for example, the lubricant fail to issue from the nozzle at a rate sufficiently fast to relieve any excessive pressure developed by violent wheel thrusts. In prior mechanisms designed for track and/or wheel lubrication, this lack of provision for minimizing the battering, 20 shock-actuation of the lubricant-ejecting parts, contributed in large measure, to their comparatively early break-down.

The invention will be best understood by reference to the drawing wherein:

Figure 1 is a plan view of an embodiment of the invention operatively applied to a railway track;

Fig. 2 is a longitudinal sectional view, taken on the line and as viewed in the direction of the arrows 2—2 of Figure 1;

Fig. 3 is a fragmentary, sectional detail view showing the means employed for securing the upper and lower members of the floating lubricant pump to the corresponding upper and lower spring units;

Fig. 4 is a fragmentary, sectional detail view, taken on the line and as viewed in the direction of the arrows 4—4 of Fig. 3; and

Fig. 5 is a fragmentary, sectional detail view, partly in elevation, taken on the line and as seen in the direction of the arrows 5—5 of Fig. 1.

Referring now to the drawing wherein similar characters of reference indicate corresponding parts in the several views, 11 designates a rail to which a lubricant reservoir or container 12 filled with suitable lubricant to any convenient height, is clampingly secured by means hereinafter described. The container 12 is somewhat reduced in height at one end and shaped to seat within the recess formed by the lateral projection of the rail head 13 and the base flange 14 of the rail on the inner side of the rail track. The reduced 45 50 55

end of the container is designed and positioned, in coacting relation with adjacent operating parts of the device, to receive superfluous lubricant from the rail head 13, as will appear hereinafter.

5 The body portion of the container 12 seats on a bracket 15 extending underneath the base flange 14 of the rail 11, and having its outer end folded upon itself, as at 16, to provide a recess wherein an outer portion of the said base flange is clampingly received. The inner end of the bracket 15 is formed with an upwardly extending flange or lug 17, having a threaded aperture receiving a screw 18, the end of which is normally pressed against a plate 19 fastened to or forming a part 15 of the rear end of the container. By turning the screw 18, the container may be clamped to the rail with a variable pressure or quickly released therefrom, when desired.

At the rear portion of and within the container 12, a series of blocks 20 are fastened by screws 21, and to the top and bottom of each of the said series of blocks, a pair of preloaded or pretensioned spring units 22 and 23 are secured by screw bolts 24 and 25.

25 Each spring unit consists of a plurality of leaves arranged in overlapping relation within the container 12, which latter also serves as a protecting house for the spring units mentioned above. The several pairs of spring units and the 30 blocks to which they are attached, are segregated in individual compartments formed by partition plates 12', whereby possible interference of the spring units, one with another, during operation, is prevented.

35 The spring unit 22 has its outer end extended to a point adjacent the rail head 13, where it is arranged to be engaged by the passing wheel flanges of railway vehicles. A rod 22' secured at its ends to the side walls of the container 40 12, and passing through the series of partition plates 12', is arranged to press downwardly and thus preload or pretension the upper spring unit 22, for a purpose which will appear hereinafter. A hardened guard plate or anvil member 26 is 45 detachably secured in any suitable manner, as by the screws 26', to the extremity of the longest leaf of the spring unit 22, and thereby serves to prevent undue wear to the surface of the latter at the contact point of the wheels.

50 Clamped between the anvil member 26 and the adjacent upper surface of the last-mentioned leaf spring, is a strip of any suitable material, such as felt 27, the outer end of which latter, as best shown in Fig. 3, is adapted to wipedly engage the inner side of the rail head 13 and thereby uniformly distribute the lubricant thereover, while returning superfluous lubricant to the container.

To the under surface of each upper spring unit 60 22 adjacent the end at which the guard plate or anvil member is arranged, a substantially U-shaped bracket 28 is secured by means of the screws 28', which latter, it is to be understood, are passed through registering openings (not shown) provided in the anvil member, felt, leaf spring and bracket 28. The bracket 28 accommodates the bent, upper nozzle portion 39 of a tube 31 forming a part of an oil-pumping unit described hereinafter. In the bore of the tube 31, a sleeve 32 is fixed, the said sleeve having a ball 33 freely supported thereon and normally closing the passageway of the sleeve and the registering bore of the tube 31 until the said ball 33 is temporarily raised by lubricant forced upward by the action of the pumping unit, when

engaged by passing vehicle wheels, as herein-after described.

Coactingly arranged within the inner periphery of the tube 31, a hollow plunger 34 is slidably mounted, the bore of the plunger being normally closed at the top by a ball 35 freely supported thereon and restrained in its movement, when impelled from its seat on the plunger, by the upward rush of lubricant during operation, by a short rod 36 arranged transversely across the 10 upper extremity of the hollow plunger 34.

The plunger 34, which has a port or opening 37 communicating with the supply of lubricant in the container 12, is circumferentially grooved, as at 38 at its closed lower end in order to 15 provide a reduced portion having a head or stud 39, the reduced portion being received in a slot or notched portion formed in the longest leaf of the lower spring unit 23. A resilient strap 41 secured at 42 to the lower spring unit and 20 having a flanged opening 43 accommodating the head 39, serves to conveniently lock or permit the quick detachment of the plunger 34, when desired. The tube 31 and coacting plunger 34, 25 with their inclosed and attached elements, form, as will be seen hereinafter, a floating oil pump supported on preloaded, self-dampening spring units.

Each of the lower spring units 23, in a manner somewhat similar to that described above in connection with the upper spring unit 22, is preloaded; i. e., maintained under some degree of tension by a lug 44 fastened to an adjacent partition plate 12', with a view to a quick dampening of their vibratory movement after contact 30 of the upper spring unit 22 by the wheels of rail-way vehicles, this quick dampening being enhanced by the comparatively small inertia of the spring units and the coacting lubricant-dispensing parts. The rod 22' and the lugs 44, in addition to their normal function, serve as preten-sioning means, and act as stops to limit the throw of their respective spring units 22 and 23, after actuation of the latter.

The body portion of the container 12 is also 45 provided with a lid or cover 45, detachably secured in any convenient manner, as by the screws 46. While the lid 45 effectively shields the major portion of the reservoir and its contents, the reduced portion is adequately protected by the 50 upper, overlapping series of spring units 22 and the strip material 27, so that the entire unit is substantially weather-proof, particular provision being made for the disposal of any water get-ting into the container, as described hereinafter. 55

A combination drain, overflow and filler pipe 47, normally closed at the top by a cap 48, is ar-ranged adjacent to and exteriorly of the contain-er 12. The pipe 47, which has an overflow pipe 60 or outlet 49 adapted to maintain an even or pre-determined head of lubricant in the reservoir, communicated with a connecting section of pipe 50 secured to an outlet pipe 51 at the bottom of and communicating with the lubricant in the container 12. The pipe section 50 is provided 65 with a drain plug 52 which serves to drain the entire contents of the reservoir, when desired.

The overflow pipe 49 of the combination drain, overflow and filler pipe 47, is particularly de-signed and adapted to automatically carry off 70 any water that has found its way into the lubri-cant container. The specific gravity of water being greater than that of oil, the said water will gravitate to the bottom and rise in the pipe 47 to its own level and after first ejecting the 75

comparatively small quantity of oil in the latter, will thereafter flow out of the overflow pipe 49 without further loss of oil. The pipe assembly 47 in combination with the container, forms one 5 of the important features of the instant invention, since, regardless of the amount of water finding its way into the container, the overflow device described above will automatically dispose of same while maintaining the normal head of 10 oil in the container 12.

The function and operation of the device, which has been in part indicated above, may be summarized as follows:

Assuming the container 12 is filled with lubricant to the height indicated in Figure 2, the said lubricant will enter the channel or port 37 in the sleeve or plunger 34 and rise in the latter to the level of the liquid in the container, the ball 35 and its seat on the top of the plunger 34, 20 constituting a ball check valve, will allow air and liquid to pass through the bore of the plunger, but will prevent the return of same, as will be readily understood. The flange of the first vehicle wheel engaging the guard plate 26, will thrust 25 downward the end of the spring unit 22 and consequently the attached tube 31 with its nozzle, thereby causing relative movement between the hollow plunger 34 and the tube 31, the first effect of which will be to expel the air in the tube 31 30 through the nozzle 30. The expelled air, after passing through the nozzle and lifting the ball 33, will be replaced by lubricant from the container 12 via the opening 37 and the bore of the plunger 34, the ball 35 in the latter being 35 thereby temporarily raised. The lubricant thereafter will be expelled from the nozzle against the inner side of the rail head 13 and be evenly distributed thereagainst by the wiping action of the flexible strip material 27. Excess lubricant at 40 the same time, as pointed out above, will be returned to the reservoir.

It will be observed that the upper and lower ball check valves, in conjunction with the hollow tube 31 and the plunger 34, serve as a double 45 acting, self-dampening, floating pump arrangement. Should the thrust communicated by a car wheel be too violent to permit the full or adequate ejection of the lubricant, the lower and somewhat more or less stiffer spring unit 23 will yield 50 so that the tube 31 with its nozzle 30 and the plunger 34, will move downwardly together. Each container assembly, with its series of independently-actuated, floating pumps, may be regarded as an operative unit, and as many of these last- 55 mentioned units, as will be desired or necessary, will be applied at the vicinity of a curve.

It is to be understood that the invention may be embodied in other specific forms without departing from the spirit or essential attributes thereof, and it is therefore desired that the present embodiment be considered in all respects as illustrative and not restrictive, reference being had to the appended claims rather than to the foregoing description to indicate the scope of the 60 invention; and it will be further understood that each and every novel feature and combination

present in or possessed by the mechanism here-with disclosed, forms a part of the invention included in this application.

Having thus described my invention, what I claim as new and desire to secure by Letters 5 Patent is:

1. In a device of the character described, a lubricant container securable to a rail, a lubricant-distributing nozzle member resiliently connected to said container, and a plunger resiliently 10 connected to the container and adapted to move independently of the nozzle member under certain operating conditions and synchronously with the nozzle member under certain other operating conditions.

2. In a device of the character described, a lubricant container, a series of lubricant-dispensing nozzle means, a corresponding series of shock-absorbing means floatingly supporting the lubricant-dispensing means on the container, a 20 series of plungers movable in and coactable with said nozzle means, a second series of shock-absorbing means floatingly supporting the plungers on the container, and partitions in the container, said partitions segregating one series of said 25 shock-absorbing means and parts carried thereby from the other series of shock-absorbing means and parts associated therewith whereby the nozzle means and plunger may move independently of each other under normal operating conditions, 30 and move as a unit when the said operating conditions communicate comparatively violent movement to the nozzle means and the plunger.

3. In a device of the character described, a lubricant container, a nozzle member resiliently 35 mounted on said container and adapted to convey lubricant from the container against a rail head, and a plunger coactable with said nozzle member and resiliently connected to said container, said plunger normally permitting reciprocal 40 movement of the nozzle member but adapted to yield when lubricant fails to issue from the nozzle member under sudden pressure.

4. In a device of the character described, a lubricant container, lubricant ejecting nozzle 45 means, shock-absorbing means floatingly supporting the lubricant ejecting means on the container, a plunger coactable with said nozzle means, and other shock-absorbing means floatingly supporting the plunger on the container, 50 whereby the nozzle means and plunger may move independently of each other under normal operating conditions and move as a unit when the actuating force exceeds a predetermined value.

5. A device of the character described comprising a plurality of independent units, each of said units being securable to a common rail and comprising in combination, a lubricant container, a nozzle member floatingly supported on the container, a plunger coactable with the nozzle member 60 and floatingly supported on the container; whereby under normal operating conditions the nozzle member and plunger may move independently of each other and also move as a unit when violently actuated.

WILLIAM F. HUCK.
